C. D. RIGG

BOW FOR MUSICAL INSTRUMENTS

Filed Jan. 13, 1921

CHARLES D. RIGG, Inventor

By

N. G. Gee

Attorney

UNITED STATES PATENT OFFICE.

CHARLES D. RIGG, OF ALTOONA, PENNSYLVANIA.

BOW FOR MUSICAL INSTRUMENTS.

Application filed January 13, 1921. Serial No. 437,002.

To all whom it may concern:

Be it known that I, CHARLES D. RIGG, a citizen of the United States, residing at Altoona, in the county of Blair and State of Pennsylvania, have invented certain new and useful Improvements in Bows for Musical Instruments, of which the following is a specification.

This invention relates to musical instruments and has for its primary object improved means of securing the bow hair in the tip end of stringed instrument bows.

Another object of this invention is to greatly simplify the means of holding the bow hair in the tip of the bow, as well as to provide means for holding the bow hair terminal in its receptacle in the bow, under the various tensions to which the bow hair of the violin bow is subjected.

20 A further object of this invention is to provide a bow hair fastening means that is applicable to the tip end of any bow used with any stringed instrument.

A still further object of this invention is 25 to provide a metallic terminal for the ends of the bow hair, and to so place this terminal in the tip of the bow that the tension on the bow hair serves to interlock the terminal with the bow.

30 With these and many other objects in view which will become more readily apparent as the nature of the invention is better understood the same consists in the novel construction, combination and arrangement 35 of parts as will be hereinafter fully pointed out, illustrated and claimed.

It will be quite readily understood by those skilled in the art to which this invention belongs that the same is susceptible 40 to some change and modification without departing from the spirit or scope of the invention, but a preferred and practical embodiment of the invention is shown in the accompanying drawings, in which:—

45 Figure 1 shows a side elevation of a violin bow having my invention applied thereto.

Figure 2 shows an enlarged view of the tip end of the bow and shows the manner 50 of applying my invention.

Figure 3 shows an enlarged view of the frog end of the bow and shows the manner of holding the bow hair in the frog.

Figure 4 shows the metallic bow hair

terminal attached to the bow hair, the same 55 being removed from its position in the tip of the bow.

Figure 5 shows a sectional elevational view of the tip end of the bow, illustrating the cavity in the tip which is adapted to receive the bow hair terminal.

Figure 6 shows the plan, side and elevational views of the bow hair terminal.

Similar reference numerals refer to similar parts throughout the several figures of 65 the drawings.

In carrying out this invention, no change is contemplated in the usual form and construction of the stringed instrument bow and hence this invention is applicable to 70 any and all makes of violin, cello and base violin bows, and consists essentially of a metallic tip or hair terminal designated by the numeral 10 which is fashioned and constructed in such manner as to firmly hold 75 the ends of the bow hair in place.

The bow hair terminal is preferably constructed of metal having some ductility and is made to present a plurality of rectangular faces. The terminal 10 is adapted to fit 80 into a specially cut cavity 11 in the bottom face 12 of the tip end 13 of the bow 14.

The face 15 of the terminal 10 is adapted to fit against the interior wall 16 of the cavity 11 while the face 17 of the terminal 85 10 is adapted to coact with the interior wall 18 of the cavity 11. The faces 19 and 20 of the terminal 10 are adapted to fit against the corresponding convergent sides of the cavity 11 such that when tension is placed 90 on the bow hair 21, the ends of each hair of which is anchored in the terminal, a simultaneous locking action is effected, which serves to effectively hold the terminal 10 in the cavity 11.

95 It will be observed that the side walls 16 and 18 of the cavity 11 are not perpendicular to the face 12 of the tip, but are preferably inclined in a direction from the frog end of the bow, while the side faces 15 and 17 100 are similarly inclined.

Before placing the bow hair in the opening A of terminal 10, a knot is tied in the bow hair, and the hair is then placed in the terminal, the knot being drawn into 105 the opening, after which the faces of the slot B are drawn together so as to firmly clamp the hair in the terminal. After this

is accomplished, it is the usual practice to pour some liquid rosin in and around the hairs to effectively cement the same together.

- An additional feature of the terminal 10 is found in the manner of cutting away the bottom of the face 17, such as to permit the spreading of the hairs over the edge 26 which is essential in order to prevent the bow hair from being bunched at this point.
- 10 When the bow hair, fitted with the terminal 10 is placed in its receptacle in the bow and tension is placed on the bow hair through the tension device associated with the frog of the bow, the tendency is to rotate the terminal 10 about the point 26 but since this rotation is restricted by the faces 15 and 17 coacting with the walls 16 and 18 an effective lock is established which serves to hold the terminal in the tip of the bow.
- 15 In the manufacture of these improved bows, it is proposed to construct the tip of the bow as above explained and the frog as explained in my former application filed November 24th, 1920, Serial No. 426,229, Patent No. 1,427,851, granted Sept. 5, 1922, and to provide the bow hair with the tip and frog clamp attached thus providing practical means whereby the rehairing of

bows for musical instruments can be easily accomplished in a few seconds.

30

I claim:

1. A tip mounting for the hair of a violin bow consisting of a tip body having an opening therein arranged at right angles to the bow string position and also provided with a slot intersecting said opening, and a shoulder formed on the body at one end of the opening and over which the hairs of the bow string may be distributed when the tip is in place.
2. A tip mounting for the hairs of a violin bow including the bow having a socket provided with walls converging toward the frog end of the bow, a terminal element for receiving the hairs and comprising a body having converging side walls thereby to fit in said socket, an opening formed in the body substantially parallel to the side walls and a slot communicating with the opening, and a shoulder disposed transversely with reference to the axis of the opening and over which the hairs may be distributed and stretched.
